UNITED STATES PATENT OFFICE.

WALTER E. LOMBARD, OF ARLINGTON, MASSACHUSETTS.

LIFTING-JACK.

1,352,207.

Specification of Letters Patent.

Patented Sept. 7, 1920.

Application filed March 26, 1919. Serial No. 288,863.

To all whom it may concern:

Be it known that I, WALTER E. LOMBARD, a citizen of the United States of America, and a resident of Arlington, in the county 5 of Middlesex and Commonwealth of Massachusetts, have invented certain new and useful Improvements in Lifting-Jacks, of which the following is a specification.

This invention relates to lifting jacks and particularly that class of jacks known as 10 screw jacks, the main object of the invention being to provide a device of this character which is self-lowering and in which the speed of lowering will be automatically controlled.

Another object of the invention is to provide a brake mechanism which will normally prevent the lowering of the load but which may be released by the foot of the 20 operator when it is desired to lower the jack.

A further object of the invention is the provision of means whereby the operating parts may be confined in the base of the lifting jack thus concentrating the preponderance of weight near the bottom of the jack.

The invention consists primarily in utilizing a non-revolute screw and a rotatable nut, said nut being driven by a driving connection adapted to positively rotate the 30 nut during the raising of the load while permitting said nut to freely revolve in the reverse direction while the load is being lowered.

The invention further consists in providing an auxiliary train of gears adapted to be actuated by the rotation of the revolute nut during the lowering operation and which train of gears has a sufficiently high ratio of speed reduction to cause its inertia 40 to substantially retard and brake the descent of the jack under its load.

The invention further consists in providing a speed retarding mechanism at the high speed end of the auxiliary train of gears whereby the speed of the rotating nut may be automatically controlled during the 45 lowering operation.

The invention further consists in providing a manually controlled brake mechanism 50 at the high speed end of the auxiliary train of gears adapted to prevent the lowering of the jack under normal conditions.

The invention further consists in providing a one-way clutch mechanism or similar 55 driving connection between the revolute nut and the low speed end of the auxiliary

train of gears whereby said train will be actuated by the rotation of said nut only during the lowering of the load.

The invention further consists in certain 60 novel features of construction and arrangement of parts which will be readily understood by reference to the description of the drawings and to the claims to be hereinafter given.

For the purpose of illustrating the invention one preferred form thereof is illustrated in the drawings, this form having been found to give satisfactory and reliable results, although it is to be understood that 70 the various instrumentalities of which the invention consists can be variously arranged and organized and the invention is not limited to the precise arrangement and organization of these instrumentalities as herein 75 shown and described, except as required by the scope of the appended claims.

Of the drawings:

Figure 1 represents a vertical section of a lifting jack embodying the principles of the 80 present invention.

Fig. 2 represents a horizontal plan of the same on line 2, 2, on Fig. 1.

Fig. 3 represents a vertical section on line 3, 3, on Fig. 1.

Fig. 4 represents a horizontal section on line 4, 4, on Fig. 1.

Fig. 5 represents a vertical section on line 5, 5, on Fig. 2, and

Fig. 6 represents an elevation of treadle 90 mechanism for actuating the brake lever.

Similar characters indicate like parts throughout the several figures of the drawings.

In the drawings, 10 is a base having an 95 upwardly extending annular flange 11 to which is bolted the vertical tubular standard 12.

Surrounding the standard 12 and movable endwise thereof is the cylindrical member 13, to the upper end of which is secured a removable cap 14. This cap 14 is provided with a downwardly extending central hub 15 to which is secured a non-revolute screw 16.

The upper end of the screw 16 is provided with a reduced shank 17 fitted into said hub 15 and retained therein by the locking pin 18.

The cap 14 is prevented from rotating 110 relatively to the movable cylindrical member 13 by the screw 19 and the said movable

member 13 is prevented from rotating relatively to the standard 12 by means of the block 20 mounted on the inner end of the threaded member 21 and positioned within 5 the vertical slot 22 in the outer wall of the standard 12.

The opposite ends of the slot 22 are closed, having abutments 23, 24 which limit the vertical movement of the cylindrical 10 member 13 in either direction as it is moved relatively to the standard 12.

The standard 12 is provided with an inwardly extending annular flange 25 on which rests a hardened ring 26 having an 15 annular groove 27 in its upper face.

In the groove 27 are positioned a plurality of balls 28 on which rests another hardened ring 29 secured to and revoluble with the revoluble nut 30.

20 This nut 30 coacts with the screw 16 and when rotated imparts vertical movement thereto.

The threads of the screw 16 and nut 30 are of such a pitch as to permit the screw 16 to 25 rotate the nut 30 during the lowering operation.

The nut 30 is provided with a downwardly extending tubular portion 31 and is provided near its lower end with a bevel 30 gear 32.

Superimposed upon the gear 32 is a hardened annular plate 33 having an annular groove 34 in its upper face in which groove are positioned a plurality of balls 35 which 35 are also positioned partially in an annular groove 36 in a hardened plate 37, the upper face of which bears against the shoulder 38 in the lower enlarged end of the standard 12.

The anti-friction members 28 and 35 permit 40 the nut 30 to freely rotate within the standard 12 and at the same time take up any end thrust thereof when it is revolved in either direction.

The gear 32 meshes with a driving gear 45 39 rotatable freely about a stud 40 pinned to the operating shaft 41 revoluble in a bearing partially formed in the flange 11 as at 42 and in the lower end of the standard 12 as at 43.

50 The operating shaft or spindle 41 is provided with a suitable operating mechanism 44 of any well-known construction.

The operating shaft or spindle 41 is provided at its inner end with a disk flange 45 having secured to its inner face a plurality 55 of pawls 46 adapted to engage a ratchet 47 pinned or otherwise secured to the gear 39.

The pawls 46 and ratchet 47 are so constructed as to impart a positive movement 60 to the gear 39 when it is desired to raise the load by means of the operating mechanism 44 and prevent the gear 39 from freely rotating independently of said shaft or spindle 41 when the load is being lowered.

65 It is obvious therefore that when the oper-

ator actuates the operating mechanism 44, the spindle or shaft 41 will be rotated in one direction only and through the pawls 46 and ratchet 47 a movement in one direction only will be imparted to the gear 39. When the 70 load is being lowered the shaft or spindle will rotate with the gear 39 in a reverse direction without affecting the operating mechanism 44.

This movement of the gear 39 by means 75 of the operating mechanism 44 will revolve the gear 32 and nut 30 in a direction relatively to the non-revolvable screw 16 to move said screw upwardly and raise the load.

During the lowering operation the downward movement of the screw 16 will rotate the nut 30 and gear 32 in the reverse direction and it is obvious that at this time the driving gear 39 will freely revolve about the stud 40 without in any manner affecting the 85 shaft 41 and operating mechanism 44, the pawls 46 riding over the teeth of ratchet 47 during this reverse movement.

In the lower end of the tubular portion 31 of the nut 30 and beneath the lower end of 90 the screw 16, is driven a plate 50 so that it will rotate with said nut 30.

Centrally disposed in said plate 50 and keyed thereto is the shank 51 of a slidable member 52 having an outwardly extending 95 flange at its lower end between which and the plate 50 is a helical spring 53.

The lower end of the slidable member 52 is provided with a plurality of ratchet teeth normally retained by the spring 53 in engagement with coacting teeth on the upper face of the gear 54.

The teeth on the slidable member 52 and the gear 54 are so constructed that during the lifting of the load the slidable member 105 52 will freely revolve with the nut 30 without effecting the rotation of the gear 54 but as soon as the nut 30 is rotated in the reverse direction during the lowering operation, the teeth will coact to cause said gear 54 to be 110 rotated by the revolution of the nut 30.

The gear is adapted to turn freely upon the stud 55 extending upwardly from the base 10 in axial alinement with the screw 16.

115 The gear 54 meshes with a pinion 55 keyed to the shank 56 of a gear 57, said shank 56 being revolubly mounted in a plate 58 secured to the upper end of the flange 11.

The gear 57 meshes with a pinion 59 also 120 loosely mounted on the stud 55 beneath the gear 54.

This pinion 59 meshes with a gear 60 keyed to the shank 61 of a pinion 62, said shank 61 being revolubly mounted in a bearing 125 in the plate 58.

The pinion 62 meshes with the gear 63 rotatable with the brake disk 64 revoluble about the stud 55.

The brake disk 64 is positioned in and 130

closes the upper end of cylindrical chamber formed by the annular fixed flange 65 extending upwardly from the base 10, said flange surrounding and being concentric to 5 the stud 55.

A brake lever 66 is pivoted at 67 to ears extending outwardly from the flange 11 and its inner end is provided with a friction pad 68 normally retained in engagement with 10 said brake disk 64 by means of a spring 68^x interposed between the flange 11 and a downwardly extending portion 69 of said lever 66.

The outer end 70 of the lever 66 is horizontal and its upper edge rounded over as indicated in Fig. 6.

Resting on this end 70 is the toe end of a foot rest 71 pivoted at 72 to the base 10 and having an upwardly extending flange 20 73 surrounding the heel portion.

The base 10 is provided with a stop 74 for the rear end of the foot rest and when the jack is in use the operator places his left foot on the foot rest 71 and normally retains it 25 in contact with the back stop 74.

With his left foot on the foot rest, he can control the operation of the jack, a slight downward pressure of the toe releasing the friction pad from contact with the brake 30 disk 64.

When the load is being lifted, the friction pad 68 in contact with the brake disk 64 prevents the rotation of any of the gears in the train between said disk 64 and the 35 one-way clutch 52—54.

When the load has been lifted it is retained in its elevated position by means of the brake pad 68 and disk 64 but as soon as it is desired to lower the load the operator 40 actuates the lever 66 to remove the pad 68 from said disk 64 and the load will immediately force the screw 16 downwardly in the nut 30 thereby causing rotation of said nut in a reverse direction.

45 This reverse movement of the nut will effect, through the one-way clutch 52—54, the rotation of the entire train of gears 54, 55, 57, 59, 60, 62 and 63 and also the rotation of the brake disk 64.

50 The train of gearing has a sufficiently high ratio of speed reduction as to cause its inertia to retard and brake the descent of the jack under its load.

55 It is self evident that owing to the fact that the brake disk is applied at the high speed end of the auxiliary train of gearing, the descent of the jack under maximum loads may be perfectly controlled by the operator by means of the brake lever 66 and 60 the lowering operation effected without jarring or injuring the jack.

To the under face of the brake disk 64 are pivoted weighted levers 75 to the shorter arms 76 of which are pivoted slideable friction members 77 normally held free from

engagement with the wall of the flange 65 by means of the springs 78.

These levers 75 and slideable friction members 77 form an automatic speed retarder when coacting with the fixed 70 flange 65.

When the jack is lowered at a normal speed the levers 75 will not operate but as soon as the speed of rotation of the nut 30 exceeds the normal, the weights 79 on the 75 levers 75 will be thrown outwardly by centrifugal action and the friction members 77 will be forced into engagement with the wall of the flange 65 and the speed will be retarded.

By constructing the jack as herein shown and described, the preponderance of weight is near the base thereby giving greater stability to the jack than would be the case where many of the parts are near the top. 80

Another advantage in placing all of the operating parts near the base is that the upper end is free from all projecting members and makes it possible to utilize the jack where other forms of jacks could not be 90 used.

By means of the auxiliary train of gears, the lowering of the jack may be controlled readily under all conditions.

It is believed that the operation and many 95 advantages of the invention will be readily understood without further description.

Having thus described my invention, I claim:

1. In a lifting jack, the combination of a 100 non-revolvble lifting screw; a revoluble nut for moving said screw endwise; driving-mechanism for said nut including means for positively actuating said nut in one direction only; means for preventing end movement of said nut; and means for controlling the rotation of said nut during the lowering operation.

2. In a lifting jack, the combination of a 110 non-revolvble lifting screw; a revoluble nut for moving said screw endwise; driving-mechanism for said nut including means for positively actuating said nut in one direction only; means for preventing end movement of said nut; and automatic means for controlling the rotation of said nut during the 115 lowering operation.

3. In a lifting jack having a chambered base, the combination of a non-revolvble lifting screw; a revoluble nut for moving 120 said screw endwise; driving-mechanism for said nut including means for positively actuating said nut in one direction only; and manually controlled means including a revoluble disk in axial alinement with said screw for controlling the rotation of said nut during the lowering operation, said disk being rotatable about a fixed stud projecting upwardly from said base.

4. In a lifting jack having a chambered 130

base, the combination of a non-revolvble lifting screw; a revolvble nut for moving said screw endwise; driving-mechanism for said nut including means for positively actuating said nut in one direction only; and automatic and manually controlled means including a revolvble disk in axial alinement with said screw for controlling the rotation of said nut during the lowering operation, 10 said disk being rotatable about a fixed stud projecting upwardly from said base.

5. In a lifting jack, the combination of a non-revolvble lifting screw; a revolvble nut for moving said screw endwise; driving-mechanism for said nut including means for positively actuating said nut in one direction only; brake mechanism normally operating to prevent the lowering of the jack and including a revolvble disk in axial alinement with said screw; and means operable by the foot of the operator for releasing said brake mechanism.

6. In a lifting jack, the combination of a non-revolvble lifting screw; a revolvble nut 25 therefor; means for preventing end movement of said nut; and driving-mechanism for said nut including means whereby said nut may rotate independently thereof in the reverse direction during the lowering operation.

7. In a lifting jack, the combination of a non-revolvble lifting screw; a revolvble nut therefor; means for preventing end movement of said nut; an operating shaft; a stud 35 thereon; a nut-driving member on said stud; and means on said operating shaft for positively moving said nut-driving member in one direction only.

8. In a lifting jack, the combination of a 40 non-revolvble lifting screw; a revolvble nut therefor; means for preventing end movement of said nut; an operating shaft; a stud thereon; a nut-driving member on said stud; a ratchet on said member; and pawls carried 45 by said operating shaft and engaging said ratchet for positively moving said nut-driving member in one direction only.

9. In a lifting jack, the combination of a non-revolvble lifting screw; a revolvble nut 50 therefor; means for rotating said nut; means for preventing end movement of said nut; and anti-friction members for taking care of the end thrust of said nut in either direction.

10. In a lifting jack, the combination of a 55 non-revolvble lifting screw; a revolvble nut therefor; means for preventing end movement of said nut; an operating shaft; and a driving connection between said shaft and nut having provision for positively rotating said nut in one direction and permitting its rotation in a reverse direction relatively to said operating shaft.

11. In a lifting jack, the combination of a non-revolvble lifting screw; a revolvble 65 nut therefor; means for positively rotating

said nut in one direction and permitting free movement thereof in a reverse direction; a fixed cylindrical member alined with said nut; an automatic speed retarding mechanism within said cylindrical member and including a revolvble disk closing the upper end of said cylindrical member; and means actuated by said nut during the lowering operation for rotating said speed retarding mechanism.

12. In a lifting jack, the combination of a non-revolvble lifting screw; a revolvble nut therefor; means for positively rotating said nut in one direction and permitting free movement thereof in a reverse direction; a fixed cylindrical member alined with said nut; an automatic speed retarding mechanism within said cylindrical member; a train of gears actuated by the rotation of said nut during the lowering operation; and a revolvble disk carrying said speed retarding mechanism and actuated by said train of gears.

13. In a lifting jack, the combination of a non-revolvble lifting screw; a revolvble nut therefor; means for positively rotating said nut in one direction and permitting free movement thereof in a reverse direction; a fixed cylindrical member alined with said nut; an automatic speed retarding mechanism within said cylindrical member; a train of gears actuated by the rotation of said nut during the lowering operation; a revolvble disk carrying said speed retarding mechanism and actuated by said train of gears; and a friction brake member coacting with said disk.

14. In a lifting jack, the combination of a non-revolvble lifting screw; a revolvble nut therefor; means for positively rotating said nut in one direction and permitting free movement thereof in a reverse direction; a fixed cylindrical member beneath and alined with said nut; an automatic speed retarding mechanism within said cylindrical member and including a revolvble disk closing the upper end of said chamber; and means actuated by said nut during the lowering operation for rotating said speed retarding mechanism.

15. In a lifting jack, the combination of a non-revolvble lifting screw; a revolvble nut therefor; means for positively rotating said nut in one direction and permitting free movement thereof in a reverse direction; a fixed cylindrical member alined with said nut; an automatic speed retarding mechanism within said cylindrical member; a train of gears actuated by the rotation of said nut during the lowering operation; a revolvble disk carrying said speed retarding mechanism and actuated by said train of gears; and a manually controlled friction brake member, coacting with said disk.

16. In a lifting jack, the combination of

- a non-revolute lifting screw; a revolute nut therefor; means for positively rotating said nut in one direction and permitting free movement thereof in a reverse direction; a 5 non-revolute stud beneath and in axial alinement with said screw but separated therefrom; a fixed cylindrical member surrounding said stud; an automatic speed retarding mechanism revolute about said 10 stud within said cylindrical member; and means actuated by the rotation of said nut during the lowering operation for rotating said speed retarding mechanism.
17. In a lifting jack, the combination of 15 a non-revolute lifting screw; a revolute nut therefor; means for positively rotating said nut in one direction and permitting free movement thereof in a reverse direction; a non-revolute stud beneath and in 20 axial alinement with said screw but separated therefrom; a fixed cylindrical member surrounding said stud; an automatic speed retarding mechanism revolute about said 25 stud within said cylindrical member; a revolute disk closing the upper end of said cylindrical member and supporting said speed retarding mechanism; and means actuated by the rotation of said nut during 30 the lowering operation for rotating said disk.
18. In a lifting jack, the combination of 35 a non-revolute lifting screw; a revolute nut therefor; means for positively rotating said nut in one direction and permitting free movement thereof in a reverse direction; a non-revolute stud beneath and in axial alinement with said screw but separated therefrom; a fixed cylindrical member surrounding said stud; an automatic speed retarding mechanism revolute about said 40 stud within said cylindrical member; a revolute disk closing the upper end of said cylindrical member and supporting said speed retarding mechanism; means actuated 45 by the rotation of said nut during the lowering operation for rotating said disk; and a pivoted brake member normally coacting with said disk.
19. In a lifting jack, the combination of 50 a non-revolute lifting screw; a revolute nut therefor; means for positively rotating said nut in one direction and permitting free movement thereof in a reverse direction; a fixed stud extending upwardly from the 55 base of the jack beneath and in axial alinement with said screw but separated therefrom; a fixed cylindrical member surrounding said stud; an automatic speed retarding mechanism revolute about said stud within 60 said cylindrical member; a revolute disk closing the upper end of said cylindrical member and supporting said speed retarding mechanism; means actuated by the rotation 65 of said nut during the lowering operation for rotating said disk; and a spring actuated
- pivoted brake member normally coacting with said disk.
20. In a lifting jack, the combination of 70 a non-revolute lifting screw; a revolute nut therefor; means for preventing end movement of said nut; means for positively rotating said nut in one direction and permitting free movement thereof in a reverse direction; a cylindrical member secured to 75 and movable vertically with said screw; and a non-movable cylindrical nut-supporting standard inclosed within said movable cylindrical member.
21. In a lifting jack, the combination of a 80 non-revolute lifting screw; a revolute nut therefor; means for preventing end movement of said nut; means for positively rotating said nut in one direction and permitting free movement thereof in a reverse direction; a flanged disk secured to the upper 85 end of said screw and movable vertically therewith; a cylindrical member secured to the flange of said disk; and a non-movable cylindrical nut-supporting standard inclosed within said movable cylindrical 90 member.
22. In a lifting jack, the combination of a 95 non-revolute lifting screw; a revolute nut therefor; means for preventing end movement of said nut; means for positively rotating said nut in one direction and permitting free movement thereof in a reverse direction; a cylindrical member secured to and movable vertically with said screw; a non-movable cylindrical nut-supporting standard 100 inclosed within said movable cylindrical member and provided with a vertical slot closed at opposite ends; and a block carried by said movable member and positioned within said slot.
23. In a lifting jack, the combination of 105 a chambered base; a cylindrical standard fixedly secured to said base; a vertically movable member surrounding said standard; a non-revolute screw secured to and movable with said movable member; speed retarding mechanism within the chamber of said base; a train of gears for actuating said speed retarding mechanism also within said chamber; a revolute nut for actuating said 110 lifting screw when rotating in one direction and said train of gearing when rotating in the reverse direction; and means for positively rotating said nut in one direction and permitting free movement thereof in a reverse direction.
24. In a lifting jack, the combination of a 115 chambered base; a cylindrical standard fixedly secured to said base; a vertically movable member surrounding said standard; a non-revolute screw secured to and movable with said movable member; brake mechanism and speed retarding mechanism within the chamber of said base; a train of gears for actuating said brake mechanism 120
- 125
- 130

and speed retarding mechanism also within said chamber; a revoluble nut for actuating said lifting screw when rotating in one direction and said train of gearing when rotating in the reverse direction; and means for positively rotating said nut in one direction and permitting free movement thereof in a reverse direction.

25. In a lifting jack, the combination of a non-revoluble lifting screw; a revoluble nut for moving said screw endwise a fixed cylindrical standard; anti-friction bearings therein for said nut; driving mechanism for said nut including means for positively actuating said nut in one direction only; mechanism for controlling the rotation of said nut; and means whereby said controlling mechanism is actuated only during the lowering operation.

20 26. In a lifting jack, the combination of a non-revoluble lifting screw; a revoluble nut for moving said screw endwise a fixed cylindrical standard; bearings therein for said nut and preventing end movement thereof; 25 driving mechanism for said nut including means for positively actuating said nut in one direction only; automatic mechanism for controlling the rotation of said nut; and means whereby said controlling mechanism 30 is actuated by said nut only during the lowering mechanism.

27. In a lifting jack, the combination of a non-revoluble lifting screw; a revoluble nut for moving said screw endwise; driving 35 mechanism for said nut including means for positively actuating said nut in one direction only; a brake mechanism including a revoluble brake disk; and means whereby said disk is rotated by said nut only during the lowering 40 operation.

28. In a lifting jack, the combination of a non-revoluble lifting screw; a revoluble nut for moving said screw endwise; driving mechanism for said nut including means for 45 positively actuating said nut in one direction only; automatic and manually controlled means for controlling the rotation of said nut during the lowering operation; and mechanism actuated by the reverse 50 movement of the nut for placing said controlling means in operation.

29. In a lifting jack, the combination of a non-revoluble lifting screw; a revoluble nut therefor; driving mechanism therefor; 55 a fixed cylindrical member; an automatic speed retarding mechanism within said cylindrical member; means for rotating said speed retarding mechanism; and a one-way clutch between said nut and rotating means 60 and adapted to be disengaged by end movement of one part thereof.

30. In a lifting jack, the combination of a non-revoluble lifting screw; a revoluble nut therefor; driving mechanism therefor; 65 a fixed cylindrical member; an automatic

speed retarding mechanism within said cylindrical member; a train of gears; a revoluble disk carrying said speed retarding mechanism and actuated by said train of gears; and a one-way clutch between said nut and train of gears and adapted to be disengaged by end movement of one part thereof.

31. In a lifting jack, the combination of a non-revoluble lifting screw; a revoluble nut therefor; driving mechanism therefor; a fixed cylindrical member; an automatic speed retarding mechanism within said cylindrical member; a train of gears actuated by the rotation of said nut during the lowering operation; and a revoluble disk carrying said speed retarding mechanism and actuated by said train of gears.

32. In a lifting jack, the combination of a non-revoluble lifting screw; a revoluble nut therefor; a fixed cylindrical standard; bearings therein for the opposite ends of said nut and preventing end movement thereof; driving mechanism therefor; a fixed cylindrical member; an automatic speed retarding mechanism within said cylindrical member; and means actuated by said nut during the lowering operation for rotating said speed retarding mechanism.

33. In a lifting jack, the combination of a non-revoluble lifting screw; a revoluble nut therefor; driving mechanism therefor; a fixed cylindrical member; an automatic speed retarding mechanism within said cylindrical member; a train of gears including an initial gear having ratchet teeth; a revoluble disk carrying said speed retarding mechanism and actuated by said train of gears; and a toothed member carried by and movable endwise relatively to said nut and adapted to engage said ratchet teeth during the lowering operation.

34. In a lifting jack, the combination of a non-revoluble lifting screw; a revoluble nut therefor; driving mechanism therefor; a fixed stud in the base of the jack; a fixed cylindrical member surrounding said stud; an automatic speed retarding mechanism revoluble about axis of said stud within said cylindrical member; a revoluble disk closing the upper end of said cylindrical member and supporting said speed retarding mechanism; and means actuated by the rotation of said nut during the lowering operation for rotating said disk.

35. In a lifting jack, the combination of a chambered base; a cylindrical standard fixedly secured to said base; a vertically movable member surrounding said standard; a non-revoluble screw secured to and movable with said movable member; speed retarding mechanism within the chamber of said base; a train of gears for actuating said speed retarding mechanism also within said chamber; a revoluble nut for actuating

said lifting screw; means for positively rotating said nut in one direction; and means interposed between nut and train of gears whereby said train will be actuated only by 5 the rotation of the nut in a reverse direction during the lowering operation.

36. In a lifting jack, the combination of a chambered base; a cylindrical standard fixedly secured to said base; a vertically 10 movable member surrounding said standard; a non-revoluble screw secured to and movable with said movable member; brake mechanism and speed retarding mechanism within the chamber of said base; a train of 15 gears for actuating said brake mechanism and speed retarding mechanism also within said chamber; a revoluble nut for actuating said lifting screw; means for positively rotating said nut in one direction and permitting free movement thereof in a reverse direction; and a one-way clutch between said 20 nut and train of gears one part of said nut being movable endwise and adapted to make a driving connection between said train and 25 nut during the lowering operation.

37. In a lifting jack, the combination of a base; a cylindrical standard fixedly secured to said base; a vertically movable member surrounding said standard; means preventing 30 the rotation of said vertically movable member; a non-revoluble screw secured to and movable with said movable member; a revoluble nut for actuating said lifting screw; means within said standard for preventing end movement of said nut while 35 permitting the free rotation thereof; means mounted on said base for rotating the nut to lift the load; and means within said base actuated by the rotation of the nut in a reverse direction during the lowering operation 40 for retarding the speed of lowering and preventing it from exceeding a predetermined limit.

38. In a lifting jack, the combination of a 45 non-revoluble lifting screw; a revoluble nut for moving said screw endwise and having

at its lower end a cylindrical portion; a member in and movable endwise of said lower end and provided with ratchet teeth on the lower end thereof; driving mechanism for said nut including means for positively actuating said nut in one direction only; a speed retarding mechanism in the base of the jack for controlling the rotation of the nut during the lowering operation; a train of gears for actuating said speed controlling mechanism; and ratchet teeth on the initial gear of said train adapted to be engaged by the teeth of said movable member when the nut is rotated in a reverse direction thereby effecting the operation of said speed controlling mechanism. 50 55

39. In a lifting jack, the combination of a non-revoluble lifting screw; a revoluble nut for moving said screw endwise and having 60 at its lower end a cylindrical portion; a bevel gear secured to said cylindrical portion; a driving gear meshing with said bevel gear and adapted to actuate said nut in one direction only; a speed retarding 65 mechanism in the base of the jack for controlling the rotation of said nut during the lowering operation, said mechanism being independent of and separated from said driving gears; a manually controlled brake 70 for normally preventing the operation of said speed controlling mechanism; a train of gears for actuating said speed controlling mechanism the initial gear of which is aligned with said screw and provided with 75 engaging shoulders; and a reciprocating member in said cylindrical portion of the nut having shoulders adapted to engage the shoulders on said gear and actuate said speed controlling mechanism only when the 80 nut is rotating in a reverse direction. 85

Signed by me at 4 Post Office Square, Boston, Mass., this 25th day of March, 1919.
